LUBRICATING APPARATUS

Frank S. Barks and Victor G. Klein, St. Louis,
Mo., assignors to Lincoln Engineering Company,
St. Louis, Mo., a corporation of Missouri

Application May 22, 1936, Serial No. 81,254

16 Claims. (Cl. 221—47.3)

This invention relates to lubricating apparatus, and with regard to certain more specific features, to an improvement upon the semi-automatic, portable, hand-injector pump, disclosed in the United States patent of Lutwin C. Rotter et al., No. 2,038,761, filed April 3, 1935, dated April 28, 1936 for lubricating apparatus.

Among the several objects of the invention may be noted the provision of the improvement over the construction of said patent application comprising the provision of a separate, one-stroke power head which is very quickly and simply attachable to any of a group of tube assemblies, each containing a different lubricant; the provision of apparatus of the class described which will permit of very convenient re-filling of each of the said lubricant tube assemblies; and the provision of apparatus of this class which is simple and compact in construction and quite easily operated. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a longitudinal section embodying the invention, certain valve parts having been eliminated for clarity;

Fig. 2 is an enlarged cross section taken on line 2—2 of Fig. 1 but showing said valve parts;

Fig. 3 is a cross section taken on line 3—3 of Fig. 2;

Fig. 4 is a fragmentary cross section taken on line 4—4 of Fig. 2;

Fig. 5 is a fragmentary cross section taken on line 5—5 of Fig. 2;

Fig. 6 is a longitudinal section of a lubricant tube with power head and outlet head removed and shown in filling position;

Fig. 7 is a side elevation of the power head which has been removed from the structure of Fig. 6;

Fig. 8 is a side elevation, parts being broken away, of the outlet head which has been removed from the tube of Fig. 6; and,

Fig. 9 is a view similar to Fig. 6 but showing a succeeding position of parts and said head of Fig. 8 applied preparatory to applying the power head of Fig. 7.

Similar reference characters indicate corre-

sponding parts throughout the several views of the drawings.

Referring now more particularly to Fig. 1, there is shown at numeral 1 a cylinder to which is removably threaded an outlet head 3, sealed at washer 20, the head 3 carrying a curved, removable outlet pipe 5 at the end of which is a nozzle 16. The pipe 5 is one of a set of similar ones that may be used. Each has a different curvature for reaching lubricant inlets in various locations. The nozzle 16 is also arranged to be removable to have other nozzles applied. The type of nozzle to be used depends upon the type of lubricant in the cylinder 1, and upon the type of receiving opening for accommodating the nozzle.

The head 3 has therein an outlet check valve 7 and is internally provided with a pump cylinder 9 adapted to slidably receive a pump plunger 11. The forward end of the plunger 11 is conic as indicated at numeral 13 and the rearward end of the cylinder 9 is beveled as shown at numeral 15 to more readily effect entry of the plunger into the cylinder on a forward stroke. The head 3 also carries an inlet connection 17 for the infilling of lubricant where the operator has available a pressure filling device.

The plunger 11 is threaded into the hexagonal shoulder 12 of a rod 21, a suitable cross passage 23 for a wrench or the like being provided for this purpose. A floating follower piston 25 is provided with suitable sealing means 27 operative both in connection with the wall of the cylinder 1 and with said rod 21. The purpose of the piston 25 is to divide the cylinder 1 (Fig. 1) into two compartments, namely, a forwardly located lubricant compartment (to the left of the piston) and a rearwardly located air compartment (to the right of the piston).

Screw-threaded permanently and sealed to the rearward end of the cylinder 1 is a diaphragm member 2 in which are air-transmitting openings 4. The diaphragm member 2 is internally threaded to removably receive by threading an adapter tube 6 which seats and seals at its bottom upon a gasket 8 held in a groove within the diaphragm member 2. At its other end the adapter cylinder 6 is permanently screw-threaded into and sealed with a head 29 having a closing diaphragm 31 therein. It will be apparent that the diaphragm 31 and the diaphragm 2 differ in that the former is without air-transmitting openings, whereas the latter has such.

Reference to Figs. 6 and 7 will show that the adapter sleeve 6 and the head 29 with attached

parts form a permanent power unit which is attachable to and detachable from the diaphragm member 2. A purpose of the diaphragm member 2 is to provide a rearward slide bearing for the 5 rod 21 and to support the air motor unit of Fig. 7 in proper concentric position.

On the left (inner) side of the diaphragm 31 is threaded a differential cylinder 33 which extends coaxially with, and into the cylinder 6. 10 The rear end of the rod 21, outside of the diaphragm 2, carries a button-like piston head 10 which contacts a differential piston 35 operating in cylinder 33. The head 10 slidably cooperates with the interior of cylinder 33, and although 15 not packed, it forms a fair piston-like seal in the cylinder. It should be noted carefully that the head 10 only abuts and is easily separable from the piston 35, as indicated by the separation of parts illustrated by Figs. 6 and 7. The purpose 20 of this is to permit the rod 21 to be actuated by said piston 10 under assembled condition, but to permit of ready disassembly and to permit the operator to use the button 10 as means for effecting manual filling operations to be described 25 under separated conditions of the power head. The bevelled lower end of cylinder 33 further facilitates the easy assembly.

The differential piston 35 is provided with a rigid, hollow extension 37 which passes through 30 the diaphragm 31, being packed therein by means of a packing 39. The extending stem 37 carries a power piston 41 upon the right-hand side of the diaphragm 31, said piston 41 operating in a closed cylinder cap 43 screwed permanently to 35 said head 29.

As shown in Figs. 2 and 3, the head 29 is provided with an air inlet fitting 47 adapted to receive an air chuck of an air line under pressure. The fitting 47 screws into a recess 49 in which 40 is a valve 51. The recess and the valve may transmit air about the valve (see Fig. 4), due to square, relieved portions 52. Thus air may pass from the fitting 47 and around the valve 51 when the valve is removed from its seat 53. However, 45 the valve is normally pressed to its seat to close off the air by means of a spring 55 and the pressure of the air itself.

The valve 51 has a stem 57 which passes with 50 clearance through a passage 59 and to the stem 61 of a second valve 63. The body of the valve 63 snugly but slidably fits the hole in which it works, so that no passage to atmosphere is provided around the valve. However, a passage 54 to atmosphere is provided in the head 29.

55 A handle 65 pivoted to the head 29 cooperates with the outer end 67 of the valve 63 so that upon pressing the handle 65, said valve 63 may be seated against its seat 45 and the valve 51 unseated from its seat 53, both against the pressure 60 of spring 55 and the air line pressure.

Thus, when the valve 51 is unseated, air may flow in from the fitting 47 into the passage 59. A side passage 71 (Fig. 1) communicates with passage 59 and passes into communication with 65 said differential cylinder 33.

Beyond the seat 45 there is also a passage 73 communicating from said passage 59 and to the region beneath piston 41 in the cylinder 43 (Fig. 3). Passage 79 leads from a point ahead of seat 70 53 to the cylinder 6.

Assuming some lubricant to be in the cylinder 1 ahead of piston 25, the operation is as follows:

By means of an air chuck, an air hose is placed in connection with the air receiving fitting 47. 75 Priming air immediately flows through the cyl-

inder 6, holes 4 in diaphragm 2, and to the cylinder 1 to force the follower 25 against the lubricant ahead of it. The plunger 11 will then be back and out of cylinder 9, because air under pressure in cylinder 6, in attempting to flow into the cylinder 33, forces back the button piston 10 against the differential piston 35. The button piston 10 has a separable sealing contact with the packing 36 of the piston 35, as shown. After contact is initiated, it is maintained, because, as will be shown, the hollow portion 38 beneath the piston 10 is in communication with the exhaust by means of a passage 40. This is because the button piston 10 has a sliding fit in the cylinder 33. Hence open cylinder 9 is primed by 15 grease under air pressure. The air, normally pressing upon the valve 51 holds it to its seat 53 to check any flow past the same.

Next, the nozzle valve 16 is placed in communication with the opening which it is desired to 20 have receive the lubricant. When the lever 65 is pressed, the exhaust valve 63 is seated, the inlet valve 51 is opened and air is admitted to the passage 59, but not to the passage 73. Hence air under pressure passes through the sideward 25 passage 71 (Fig. 1) to the cylinder 33 to impress its force upon the top of differential piston 35 to produce a balanced pressure condition and hence canceling the return action of air beneath the button piston 10.

Some of the charge of air which enters the cylinder 33 passes through the hollow stem 37, via the port 71 and out into the cylinder 43, where it impresses its force upon the top of power piston 41 to force down the rod 37 and piston 35 35 against the piston 10. This forces rod 21 to push plunger 11 into the cylinder 9 to effect a single discharge of lubricant therefrom. In the meantime air exhausts from beneath the piston 41 via passage 54. Fig. 1 illustrates the discharging 40 position of parts. The air pressure in cylinder 33 and the air pressure in cylinder 6 being equal, the air pressure on opposite sides of the combined pistons 10 and 35 is equalized, thus leaving the full pressure on piston 41 without 45 any back pressure to resist it in forcing the rod 21 through a discharging stroke.

Upon releasing the handle 65, the flow of air to the passage 59 is cut off by valve 51, and thus flow is cut off to the top of the power piston 41. 50 At the same time the valve 63 is opened so that the air in cylinder 43 above piston 41 may exhaust to cylinder 33 through stem 37 and the air from cylinder 33 exhausts via port 71, passage 59, 55 passage 73 and out of port 54. Simultaneously, the pressure in the hollow portion 38 between 60 pistons 10 and 35 is exhausted through ports 40, 71, cylinder 33, passages 71, 59, 73, cylinder 43, and port 54. The entire exhausting operation 65 and hence charging operation into cylinder 9 is due to the return movement of head 16 and piston 35 (which are sealed), under the unbalanced condition of pressure therebeneath. Inasmuch as the priming pressure on piston 10 is in excess of the released pressure in the space 38, the 70 cupped edge of the piston 10 assumes its seal with respect to packing 36 of the differential or driven piston 35, and there is thus effected a pneumatic connection between this without any leakage whatsoever to the cylinder 33 from the cylinder 6. Thus another charge of lubricant is drawn or forced into said cylinder 9.

In view of the fact that pressure of air is maintained behind the follower piston 25 and in the cylinder 1 because of passage 79 leading from 75

a point ahead of the valve 51 in communication with the inlet fitting 47, every time that an air line is attached to the fitting 47, priming air is immediately forced into the cylinder 1 behind the follower 25 and said pressure is released as soon as the air line is removed. Thus no reliance is placed upon holding an isolated charge of air in the cylinder 1. Each time that a connection is made, the device is primed and made ready for a power stroke. It will be seen that since the power unit is uncoupled only after the lever 65 has been released that the pistons 41 and 35 will be always in return position (see dotted lines, Fig. 7) when the power unit is re-applied. Also, since the air hose is disconnected from fitting 47 prior to unscrewing the power unit, there will be zero pressure in the cylinders 6 and 1 upon their separation and after the power unit parts are in their Fig. 7 dotted-line positions.

20 Since the above is true, the piston 10 will be seen to have always been pushed part way out upon separation, whereby it is in a position to be easily grasped for refilling.

One of the advantages of the invention is that 25 a lubricant service station may carry various assemblies of lubricant-containing cylinders 1, with lubricants of different kinds respectively therein, such as, for instance, water-pump lubricant, universal joint lubricant, chassis lubricant, and the like. For all of these, only one one-stroke air 30 motor or power unit, such as shown in Fig. 7, needs to be carried, because said unit may be screwed into the diaphragm member 2 of any lubricant-carrying assembly. For instance, an 35 operator may screw the power unit to a cylinder 1 carrying water pump lubricant and lubricate a water pump. Then, he may unscrew the power unit from said water-pump-lubricant-containing cylinder and apply it to a cylinder 1 containing, 40 say universal joint lubricant, and proceed to lubricate such a joint. Thus a variety of supplies of lubricants are ready, and the user need purchase only one of the power units. In this respect, the present invention is an improvement upon the 45 one described in said application. Furthermore, it is advantageous in comparison with other single power unit and multi-cylinder devices in that the power unit is of the "single-shot" variety which gives economy in dispensing and the connection is easier, simpler and more sure by reason of the mere abutment between members 10 and 35 which are pneumatically held together.

Furthermore, the movement of assembling the power unit with the reservoir is all that is required to abut the pistons 10 and 35 for subsequent automatic operation.

One mode of filling the device is to connect a lubricant filler line to the inlet 17 and force lubricant therethrough against piston 25 which 50 is thus automatically forced back. At this time there is no air line connected to the fitting 47 so that the air pressure behind the follower piston 25 is atmospheric and as the follower proceeds inwardly, the air is exhausted through port 55 79 and open fitting 47. The diaphragm 2 functions as a stop to automatically limit the travel of a follower piston 25 and consequently the charge of the lubricant.

Sometimes the user is not equipped with filling 70 apparatus of the class above referred to. In this event he unscrews the power component shown in Fig. 7. The member 2 remains on the cylinder or barrel 1. He also unscrews the outlet head 3 from said cylinder 1. He then 75 grasps the exposed button piston 10 and with-

draws the rod 21, thereby causing the shoulder 12 on said rod to contact the piston 25 to pull back the latter. Then if the lower end of the cylinder 1 is in a lubricant supply 14 such as shown in Fig. 6, the suction will draw in a charge 5 of lubricant. A filler plate or a paddle may also be used as known. After the charge is complete the head 3 is applied as shown in Fig. 9. The rod 21 may then be pushed back into its position within the cylinder 1 and the piston 25 will retain its position at the upper end of the cylinder 1. This is because the lubricant in the cylinder blocks movement of the piston 25 with the head 3 in position. Thereafter the assembly of cylinder 1, outlet head 3 and diaphragm 2 is ready for 15 use by applying a power unit. A group of these each having a different lubricant therein, may be kept in readiness, say in a rack.

The threaded connection between the cylinders 6, 33, 43 and the member 29 is a permanent one; 20 whereas the connection between said cylinder 6 and the diaphragm member 2 is a quick-detachable connection. The threads between the cylinder 6 and the diaphragm member 2 are relatively coarse and of a nature to be easily started. The 25 pattern on the member 29 is such that slippage of the hand is prevented in rotating the motor unit, and the diaphragm member 2 is externally knurled. Usually the operator grasps the knurled diaphragm member 2 with his left hand and 30 screws in the motor unit with the right hand.

In view of the above, it will be seen that the several objects of the invention are achieved and other advantageous results attained.

As many changes could be made in carrying 35 out the above constructions without departing from the scope of the invention, it is intended that all matter contained in the above description or shown in the accompanying drawings shall be interpreted as illustrative and not in 40 a limiting sense.

We claim:

1. In apparatus of the class described, a fluid reservoir, a reciprocating pump at one end of said reservoir adapted to withdraw lubricant 45 from the reservoir and eject it, supporting means on the other end of the reservoir, an operating means passing from said pump through the reservoir and slidably through said supporting means, a follower dividing said reservoir into a 50 lubricant compartment and an air compartment and surrounding said operating means, a control member on said operating means outside of said supporting means, an air power unit, quick-detachable means between said power unit and said 55 supporting means, a movable part on said power unit adapted upon one stroke merely to abut said control member to move the operating means to eject lubricant, and means whereby said power unit applies air to the control member to effect 60 reversal of movement of said control member to prime the pump and return the power unit to starting position.

2. In apparatus of the class described, a fluid reservoir, a reciprocating pump adapted to withdraw lubricant from the reservoir and eject it, an operating member passing from said pump and from the reservoir, a control member on said operating member located exteriorly of the reservoir, and a quick-detachable air power unit 65 adapted to be fastened to said reservoir and having a part adapted merely to abut said control member to operate the pump to eject, and to apply air to said control member to operate the pump to return from ejection position and to 70 75

- force back the abutting part on the power unit.
3. In apparatus of the class described, a fluid reservoir, a reciprocating pump adapted to withdraw lubricant from the reservoir and eject it, an operating member passing from said pump and from the reservoir, a control member on said operating member located exteriorly of the reservoir, a follower in the reservoir movable by said operating member to draw in fluid, said control member being manually operable from the outside of the reservoir, a power unit, a quick-detachable connection between the power unit and the reservoir, a pressure member in the power unit, said pressure member in the power unit being adapted to force said operating member on one stroke of the power unit, and said power unit having means to cause said operating member to force the driving means to starting position on the next stroke.
- 20 4. In apparatus of the class described, a fluid reservoir, a reciprocating pump adapted to withdraw lubricant from the reservoir and eject it, an operating means passing from said pump through the reservoir and to a point outside thereof, a control member on said operating means outside of the reservoir and a quick-detachable power unit for the reservoir, means in the power unit adapted when attached to abut said control member to actuate the pump upon one power stroke, and means in the power unit adapted to empower the control member to force the parts in the power unit back to starting position.
- 25 5. In apparatus of the class described, a fluid reservoir, a reciprocating pump adapted to withdraw lubricant from the reservoir and eject it, an operating member passing from said pump and from the reservoir, a control member on said operating means exteriorly of the reservoir, and a quick-detachable single-stroking pneumatic power unit adapted to be fastened to said reservoir and by its movement of attachment to abut with said control member, means whereby the pump is operated through said abutment by operation of the power unit, and means in said power unit energizing the control member to set the power unit to starting position.
- 30 6. In apparatus of the class described, a fluid reservoir, a reciprocating pump at one end of said reservoir adapted to withdraw lubricant from the reservoir and eject it, air-transmitting supporting means on the other end of the reservoir, an operating member passing from said pump through the reservoir and slidably through said supporting means, a follower dividing said reservoir into a lubricant compartment and an air compartment and surrounding said operating means, a control member on said operating means outside of said supporting means, an air motor, quick-detachable means between said air motor and said supporting means, the quick-detachable connection comprising an air-tight cylinder, an inside cylinder therein, a piston in said inside cylinder adapted to receive pressure to force said piston against said control member, said control member slidably fitting said inside cylinder, whereby air in said air-tight cylinder will force the control member to cause said pump to effect a suction stroke and force said motor to a starting position, said air also passing through said air transmitting support to said air compartment.
- 35 7. In apparatus of the class described, a fluid reservoir, a reciprocating pump at one end of said reservoir adapted to withdraw lubricant from the reservoir and eject it, air-transmitting sup-

porting means on the other end of the reservoir, an operating member passing from said pump through the reservoir and slidably through said supporting means, and a follower dividing said reservoir into a lubricant compartment and an air compartment and surrounding said operating means, a control member on said operating means outside of said reservoir, an air motor, quick-detachable means between said air motor and said supporting means, a cylinder on the motor, a piston in said cylinder adapted to receive pressure to force said piston against said control member, said control member slidably fitting said cylinder, and means for actuating the air engine to move the control member in one direction and to apply air to the control member to move the engine in a reverse direction, said control member being separable from the air motor upon removal of the latter.

20 8. In apparatus of the class described, a fluid reservoir, a reciprocating pump adapted to withdraw lubricant from the reservoir and eject it upon suction and compression strokes respectively, an air motor having a quick-detachable connection with the reservoir for applying super-atmospheric priming pressure inside of the reservoir and to the lubricant, a power means in said air motor, a differential cylinder therein, a control piston in said differential cylinder reciprocating with the pump, a differential piston in said differential cylinder and reciprocating with the power means, said control piston cooperating with said differential piston means for introducing air pressure on the power means in a direction to drive the pump to an ejecting stroke and at the same time to the differential piston to balance pressure thereon from said control piston.

25 9. In apparatus of the class described, a fluid reservoir, a reciprocating pump adapted to withdraw lubricant from the reservoir and eject it upon suction and compression strokes respectively, and air motor having a quick-detachable connection with the reservoir for applying super-atmospheric priming pressure inside of the reservoir and to the lubricant, a power means in said air motor, a differential cylinder therein, a control piston in said differential cylinder reciprocating with the pump, a differential piston in said differential cylinder and reciprocating with the power means, said control piston cooperating with said differential piston means for introducing air pressure on the power means in a direction to drive the pump to an ejecting stroke and at the same time to the differential piston to balance pressure thereon from said control piston, and subsequently to exhaust the said introduced air and to introduce air to prime the reservoir and to press the control piston toward said differential piston to return the motor.

30 10. In apparatus of the class described, a pump, a lubricant supply chamber, a follower in said chamber, a separate air motor for operating said pump, a quick-detachable connection between said air motor and said supply chamber, a differential cylinder associated with said air motor, control means extending from the pump and adapted to fit into said differential cylinder when the air motor is applied to the chamber, a differential piston carried by the air motor and in said differential cylinder and abutting said control means, and valved means on the motor adapted in one position of parts to direct air behind said follower and against said control means while effecting exhaust from the differential piston, and in another position to direct air against the said dif-

ferential piston and to the air motor to energize the abutting control means to operate the pump.

11. In apparatus of the class described, a pump, a lubricant supply chamber, a follower in said chamber, an extension from said pump passing through said follower, a piston head on said extension adapted to be reached to effect in-drawing of the follower by pulling out the extension, an air motor, a quick-detachable connection between said air motor and said chamber, a differential cylinder associated with said air motor and slidably accommodating said piston head, a differential piston in said differential cylinder abutting said piston head, and valve means adapted in one position to direct air behind said follower and against said piston head to effect a suction stroke of the pumping means and priming thereof, and in another position thereof to direct air to effect a pumping stroke of the pump and at the same time to direct air above said differential piston to balance the pressure from the abutting piston head.

12. In apparatus of the class described, a lubricant supply compartment, a reciprocating pump adapted to withdraw and eject lubricant from said compartment, a follower in said compartment forming a lubricant chamber on the side nearest the pump and providing an air chamber on the other side, an extension movable with said pump, a control member carried by said extension, the arrangement between the follower and said control member being such that as the pump is driven by the control member through said extension to draw in a charge, said follower is driven to force the charge to the pump, an air engine, a quick-detachable connection between said air engine and said compartment, a differential cylinder on said engine, a surrounding air-tight cylinder for delivering air under pressure to said air chamber, a power piston, a differential piston in said differential cylinder, and means joining said power piston and differential piston, said control member and differential piston merely abutting when the engine is assembled to the chamber, and valve means for introducing air to said differential piston and for introducing air to such side of the power piston as will force the pump to execute an ejecting stroke.

13. In apparatus of the class described, a lubricant supply compartment, a reciprocating pump adapted to withdraw and eject lubricant from said compartment, a follower in said compartment forming a lubricant chamber on the side nearest the pump and providing an air chamber on the other side, an extension movable with said pump, a control member carried by said extension, the arrangement between the follower and said control member being such that as the pump is driven by the control member through said extension to draw in a charge, said follower is driven to force the charge to the pump, an air engine, a quick-detachable connection between said air engine and said compartment, a differential cylinder on said engine, a surrounding air-tight cylinder for delivering air under pressure to said air chamber, a power piston, a differential piston in said differential cylinder, and means

joining said power piston and differential piston, said control member and differential piston merely abutting when the engine is assembled to the chamber, and valve means for introducing air to said differential piston and for introducing air to such side of the power piston as will force the pump to execute an ejecting stroke and alternatively for introducing air against the control member to effect a pump suction stroke and also against the follower.

14. In apparatus of the class described, a reservoir, a pump, operating means for said pump extending from said reservoir, a priming means for the pump cooperating with said operating means for infilling of fluid, manual control means on the operating means exteriorly of the reservoir adapted to be manipulated to cause the operating means to move the priming means to effect an infilling of the reservoir, and a power unit having a quick-detachable connection with said reservoir and adapted upon a manipulation to move said manual control means to effect a single ejection of lubricant and by another manipulation to power said control means to force the power unit and the pump to starting position.

15. In apparatus of the class described, a fluid reservoir, a reciprocating pump adapted to withdraw lubricant from the reservoir and eject it, an operating member passing from said pump and from the reservoir, a control member on said operating member located exteriorly of the reservoir, and a quick-detachable air power unit adapted to be fastened to said reservoir, a part of the power unit abutting said control member whereby the control member may be forced to operate the pump to eject, and means in the power unit to apply air to said control member to operate the pump to return from ejection position and to force back the abutting part on the power unit, said control member and said abutting part on the power unit having a pneumatic sealing connection at the abutment therebetween.

16. In apparatus of the class described, lubricant pumping means adapted to be primed with lubricant under pressure obtained from air under superatmospheric pressure, a member extending from the pumping means adapted to be controlled to effect pumping, a quick-detachable air motor for said lubricant pumping means, a driving piston in said motor, a driven piston, a cylinder surrounding said driven piston and slidably accommodating said controlled member, said controlled member and driven piston having a sealing abutment in the cylinder, and means for balancing super-atmospheric pressure on opposite sides of the sealed driven piston and controlled member while said pressure is applied to the lubricant pumping means for priming purposes and to the power piston for driving purposes, and means for exhausting pressure from the power piston and from one side of the organization of sealed driven piston and controlled member, whereby said priming air effects a return action on the air motor by driving said sealed differential piston and controlled member.

FRANK S. BARKS.

VICTOR G. KLEIN.
